CHEMICAL PROCESS

Alfred W. Francis, Woodbury, N. J., assignor to
 Socony-Vacuum Oil Company, Incorporated,
 New York, N. Y., a corporation of New York

No Drawing. Application June 28, 1939,
 Serial No. 281,651

3 Claims. (Cl. 196—10)

This invention relates to the production of high grade motor fuels. More particularly the invention relates to an improved method of synthesizing high grade motor fuels from olefines and paraffins of relatively low molecular weight.

In recent years the demand from the automotive and aviation industries for motor fuels of increased power has stimulated and commanded the attention of a tremendous amount of research. Since the compound iso-octane typifies high grade fuels, a large part of the research has been directed towards producing fuels consisting predominantly of compounds which approximate iso-octane; some other work has aimed at increasing the aromatic content of fuels. The processes developed for producing fuels of greater power are in general of three types, namely, re-arrangement processes such as cyclization and isomerism; pyrolysis or the selective breaking down of larger molecules to the molecules desired, e. g., de-polymerization and de-alkylation; and synthesis or the selective building up of smaller molecules to the molecules desired, such as alkylation and polymerization with hydrogenation.

One of the more promising of the alkylation processes which has been developed is the so-called "cold-acid" process wherein isoparaffins are alkylated with free olefines (except ethylene) in the presence of a concentrated sulfuric acid catalyst at temperatures below about 30-40° C. The usual temperatures of operation in the "cold acid" process for alkylating with free olefines are from about -12° C. to about 30° C., and in order to eliminate as much polymerization of the olefines as possible, the concentration of olefines is kept relatively low by adding the olefines slowly to the reaction mixture. The sulfuric acid used in the "cold acid" process must be concentrated and its exact strength depends somewhat upon the particular olefines being used. For instance with propylene at about 20° C., the acid used is upwards of 100% and with isobutylene an acid around 96-97% may be used. In this process only isoparaffins are alkylated, any normal paraffins that might be present are unaffected. Yields of high grade fuel appreciable above 100% based on the olefine content are obtained.

It is an object of this invention to provide an improved method of combining paraffins and olefines to obtain high yields of high octane motor fuel.

A more specific object of my invention is to provide an improved method of combining isoparaffins and olefines to obtain high yields of high octane motor fuel.

Still another specific object of my invention is to provide an improved method of combining isoparaffins and propylene at relatively low temperatures in the presence of sulfuric acid to pro-

duce high yields of high octane motor fuel which permits the use of less concentrated sulfuric acid.

My invention comprises an improved method whereby olefines are first reacted with sulfuric acid to form alkyl esters thereof and then the alkyl esters are reacted with paraffins in the presence of concentrated sulfuric acid at a relatively low temperature suitably adjusted with respect to the acid concentration that a high yield of high octane motor fuel is obtained.

It should be noted that all the reagents, i. e., all the alkyl esters and paraffins, should not be mixed in batch as poor yields will be obtained, but rather the reagents should be mixed slowly. In usual practice it has been found advisable to add the alkyl esters slowly to the paraffins over a period of, for example, about 60 minutes. This time may vary with different operations and with variations in yields that may be permitted; however, in any event, the mixing should be gradual and somewhat of this order rather than in batch.

Thus the alkyl sulfates in my process are added slowly to the reaction mixture as are the olefines in the "cold-acid" alkylation with free olefines. However, the process of reacting an alkyl sulfate with an isoparaffin rather than using free olefines as in the so-called "cold-acid" process has several distinct advantages. In the first place, polymerization of olefines is almost completely eliminated so that, for instance, in the case of diisopropyl sulfate and isobutane, at least 80% of the product may consist of branched chain heptanes. Further, gases which are relatively low in olefine content may be employed in making the alkyl sulfates, since paraffinic gas diluents are unabsorbed. On the contrary when alkylating with free olefines mixed with a considerable concentration of other inert gases such as straight chain paraffins, e. g., propane or normal butane, the reactants are diluted, the pressure in the reaction vessel is increased and production capacity of the apparatus is decreased. Since normal paraffins are commonly in admixture with olefines supplies and since normal paraffins are inert in the so-called "cold acid" process such factor is a disadvantage. A further advantage in the use of alkyl sulfates rather than free olefines is that the absence of free olefines, when using alkyl sulfates, diminishes the reduction and fouling of the acid catalyst so that it can be re-used more times, thus decreasing the consumption of acid.

Perhaps the most important of the advantages of the present process is the fact less concentrated acid can be used for the catalyst. As indicated hereinabove the concentration varies, other factors being equal, with the particular olefines being used. However, as representative, it might be noted that when isoparaffins are alkylat-

ed at about 30° C. with free olefines, using propylene as the olefine, an acid concentration over 100%, e. g. 101%, is recommended. On the other hand when combining propylene indirectly with isoparaffins at about 30° C. by means of diisopropyl sulfate, an acid concentration around 97% is satisfactory. In addition to the obvious economical advantage from using less concentrated acid, there is the further economical advantage in that the acid is "fouled up" in proportion to its concentration, and therefore more concentrated acid is fouled more and hence can be re-used fewer times, or, at least, requires more expensive regeneration and replenishing.

I have discovered further that very important relationships exist between the temperature and acid concentration that may be used in my process if high yields are to be obtained. In order for a process to be commercially practical it should give a yield of at least 100% based on the olefine content, and preferably more. I have found that there is a lower limit temperature of operation below which such yields cannot be obtained. For instance, in working with propylene (i. e., using diisopropyl sulfate), at temperatures below about 5° or 7° C., it would be impossible to obtain high yields, since acid which is sufficiently concentrated for these temperatures of operation freezes at such temperatures. For the above reason a temperature below approximately 7° C. cannot be used economically when reacting with diisopropyl sulfate unless possibly the freezing point of the acid is lowered in some manner which is not otherwise detrimental. On the other hand two high temperatures should not be used, as undesirable side reactions will be encountered. Temperatures around about 50° to 60° C. are at present considered optimum, and while we prefer to use temperatures around 50° to 60° C. or lower, temperatures up to about 100° C. could probably be used satisfactorily.

Furthermore, I have found that for the temperatures which are within the operative range, and can be used, there is a minimum acid concentration that can be used with each temperature, and below which high yields cannot be obtained. This discovery is fully illustrated in the following data obtained from reacting diisopropyl sulfate with isobutane under various conditions:

Table

Run No.	Temper- ature (Degrees C.)	Concen- tration Per cent	Yield (based on olefine)	Concen- tration plus $\frac{1}{4}$ temp.
1.	0	98	52	98
2.	2	95	9.5	95 $\frac{1}{4}$
3.	2	97	21.4	97 $\frac{1}{4}$
4.	7	98.5	117	98 $\frac{3}{4}$
5.	26	93	64.3	96 $\frac{3}{4}$
6.	26	95	162	98 $\frac{3}{4}$
7.	26	97	178.5	100 $\frac{3}{4}$
8.	30	94.5	162	98 $\frac{3}{4}$
9.	42	94.5	138	100 $\frac{1}{2}$
10.	50	93	134	100 $\frac{1}{4}$
11.	50	94.5	190	101 $\frac{1}{4}$
12.	50	95	188	102 $\frac{1}{4}$
13.	50	96	186	103 $\frac{1}{4}$
14.	60	92	170	100 $\frac{1}{4}$
15.	60	90	138	98 $\frac{3}{4}$
16.	70	90	121	100

Runs 1 and 4 above were made at approximately the freezing points of the acids used, and, therefore, were approximately the minimum temperature for that concentration of acid. Run 1 gave a poor result while run 4 gave a passable

result just above the more or less arbitrarily considered commercially practical yield of 100%. Accordingly the 7° C. of run 4 might be considered to be approximately the lower temperature limit for obtaining high yields with diisopropyl sulfate.

It was further noted that an increase of about 7° C. permitted a reduction in the acid concentration of roughly 1%. Therefore a rule was formulated which appears to be suitable for roughly determining the permissible operating conditions. Thus it appears the percent concentration of the acid plus one-seventh of the temperature in degrees centigrade should equal a value greater than 98 and preferably above 100. It will be noted that in run 1 where the value of concentration plus one-seventh of the temperature was exactly 98, a poor yield (52%) was obtained, and in all the other cases where the value was below 98 poor yields were obtained. On the other hand, in all cases where this value was above 98, high yields were obtained. This rule probably applies more exactly near the middle of the operative temperature range than near the bottom or the top of this temperature range, and while it is probably not a precise rule, it does serve to at least approximate operating conditions.

A further important feature of the present invention is the fact there are optimum temperatures around 50° to 60° C. rather than around 20° C. as in the cold-acid process. This advantage is realized because (1) temperature control by cooling water is cheaper than by refrigeration and (2) higher temperatures permit the use of weaker acid which is less fouled and can doubtless be used over again more times.

The above values will vary somewhat for olefines other than propylene and, in general, will permit wider limits because of the less reactivity of propylene. Because the conditions vary somewhat with the olefines used, to some extent with the paraffins used and various other factors, definite limitations to all operating conditions for all reactants could not be set feasibly. However such is believed unnecessary as I have indicated the general operating range setting forth many operable conditions and the precise limits of operation would in most cases be of little importance. Moreover, if desired, determination of the precise limits of temperature and acid concentrations that will give my improved results for any particular operation may be easily made by a few tests as above outlined for diisopropyl sulfate and isobutane. The acid concentration in any operation of my process would not be below about 85% and for good results probably should never be below about 90%.

As mentioned, one of the advantages of the present process results from the fact that gaseous mixtures which are relatively dilute with respect to olefines may be used as one of the raw materials. However, it is to be understood that any suitable source of olefines may be used including pure olefines. The olefines which are used should be of relatively low molecular weight such as propylene and butylene so that when they are compounded with the paraffin, the compounded molecules will have a boiling point within the gasoline boiling range.

The paraffins employed preferably comprise predominantly isoparaffins, for example, isobutane and isopentane. These isoparaffins may be used in a pure form or may be mixed with other inert constituents. Moreover, the isoparaffins may be used in admixture with normal

paraffins such as propane, butane, pentane, etc. Since isoparaffins are often found in admixture with normal paraffins it is of material advantage to be able to use the mixture. By the present process part of the normal paraffins will also be reacted with the alkyl sulfate, thus increasing the yield and thereby distinguishing from and giving

20% NaOH, and distilled, giving 288 ml., or 199 g., a yield of 75% of the theoretical from the ester used or 178.5% based on the olefine content. The portion boiling below 150° C. (84%, sp. gr. 0.680) amounts to a 150% yield of this portion based on olefine content. The distillation range is as follows:

Percent	Initial	5	20	50	65	70	84	90	96	
Temperature, degrees centigrade		40	76	81	87	93	99	150	159	183

an advantage over alkylation with free olefines wherein normal paraffins are inert constituents. Of course, if desired, only normal paraffins could be reacted with the alkyl sulfates. However, the yield in such cases is much lower and the resulting compounds have lower octane ratings.

In preparing the alkyl sulfates, the olefines or mixtures containing olefines, are reacted with concentrated sulfuric acid until substantially all the olefines have been absorbed. The resulting mixture comprises alkyl sulfates, alkyl sulfuric acid and sulfuric acid. Since this "sulfated" mixture contains both alkyl sulfate esters and alkyl sulfuric acid esters that may be reacted with paraffins, as well as, sulfuric acid which may act as part of the catalyst, such mixture may, and preferably is, admixed directly with the paraffins. However, since the mixture is highly corrosive, it would be advisable to first neutralize the reaction product before introducing it into reaction with the paraffins, if the only apparatus available was subject to corrosion.

The formation of diisopropyl sulfate, for instance, may be carried out in the following manner:

Ninety-eight percent sulfuric acid is saturated with propylene using vigorous agitation and keeping the temperature below 0° C. One mole of acid absorbs 1.75 moles of propylene. The colorless product contains 0.75 mole of diisopropyl sulfate and 0.25 mole of isopropyl sulfuric acid. If it is desired to neutralize the product, this may be done by washing with water and dilute alkali, leaving substantially pure diisopropyl sulfate, which is neutral, stable, and non-corrosive. Its specific gravity is about 1.1.

The following examples are given in order to further illustrate the invention. However, it is to be understood the invention is not to be limited thereto as there may be variations from these examples without departing from the scope of the invention:

Example I

An injecting pump of 220 ml. capacity was filled with neutralized diisopropyl sulfate liquid prepared as outlined above. A Monel autoclave of 1060 ml. capacity was charged with 430 ml. (796 g.) of 97% sulfuric acid and 300 ml. (177 g.) of liquid isobutane, and warmed to 20° C. at which the pressure was 35 lbs. Vigorous agitation was started, and the ester was injected into the autoclave during 65 minutes. The temperature rose gradually to about 30° C. and the pressure to 42 lbs. and then dropped to 28 lbs. Agitation was continued 30 minutes after all the ester was added, however such additional agitation is unnecessary.

The pressure was relieved, recovering 21 g. of excess isobutane. The product was poured out and separated into two layers. The lower acid layer, 910 g., consisted of 95% sulfuric acid and small amounts of organic matter. The colorless upper layer of 0.680 sp. gr. was washed with 95% sulfuric acid to remove traces of ester, then with

15 20% NaOH, and distilled, giving 288 ml., or 199 g., a yield of 75% of the theoretical from the ester used or 178.5% based on the olefine content. The portion boiling below 150° C. (84%, sp. gr. 0.680) amounts to a 150% yield of this portion based on olefine content. The distillation range is as follows:

15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 I claim:

1. The process of alkylating a paraffin with an olefin which comprises absorbing the olefin in concentrated sulfuric acid to form an absorption mixture thereof and reacting a paraffin with the absorption mixture of olefin and concentrated sulfuric acid in the presence of concentrated sulfuric acid under alkylation conditions of operation to effect alkylation of the paraffin with said olefin, said alkylation reaction being carried out at a temperature between about 50 and about 60° C. and in the presence of sulfuric acid of such concentration that the percent concentration of the acid used plus one-seventh of the temperature used in degrees centigrade equals a numerical value of at least 100.
2. The process of alkylating an isoparaffin with propylene which comprises absorbing the propylene in concentrated sulfuric acid to form an absorption mixture thereof and reacting an isoparaffin with the absorption mixture of propylene and concentrated sulfuric acid in the presence of concentrated sulfuric acid under alkylation conditions of operation to effect alkylation of the

isoparaffin with said propylene, said alkylation reaction being carried out at a temperature between about 50 and about 60° C. and in the presence of sulfuric acid of such concentration that the percent concentration of the acid used plus one-seventh of the temperature used in degrees centigrade equals a numerical value of at least 100.

3. The process of synthesizing hydrocarbons of gasoline boiling range which comprises combining propylene with concentrated sulfuric acid to form diisopropyl sulfate and reacting a light isoparaffin with said diisopropyl sulfate in the presence of concentrated sulfuric acid under alkylation conditions of operation to effect alkylation of said isoparaffin with said propylene, said alkylation reaction being carried out at a temperature between about 50 and about 60° C. and in the presence of sulfuric acid of such concentration that the percent concentration of the acid used plus one-seventh of the temperature used in degrees centigrade equals a numerical value of at least 100.

ALFRED W. FRANCIS.
